UNITED STATES PATENT OFFICE.

WILLIAM S. THOMAS, OF LOCK HAVEN, PENNSYLVANIA, ASSIGNOR OF ONE-HALF TO
JAMES E. BUZZARD, OF LOCK HAVEN, PENNSYLVANIA.

SPARK-PLUG.

1,221,923.

Specification of Letters Patent. Patented Apr. 10, 1917.

Application filed August 10, 1916. Serial No. 114,133.

To all whom it may concern:

Be it known that I, WILLIAM S. THOMAS, a citizen of the United States, residing at Lock Haven, in the county of Clinton and State of Pennsylvania, have invented certain new and useful Improvements in Spark-Plugs, of which the following is a specification.

My invention consists of an improved form of spark plug and is especially serviceable for use in connection with internal combustion engines. One object of my invention is to produce a spark plug which will efficiently protect its electrodes and adjacent elements from carbon deposit.

Another object is to so produce my improved spark plug that it will be of simple construction and the several parts may be quickly and easily removed and assembled. A further object of my invention is to prevent the electrodes from injury both while in action and during the assembling of the same.

Another object is to so construct my improved spark plug that it may be easily and cheaply manufactured and can be adjusted to suit different conditions and types of engines.

These objects, and other advantageous ends which will be described hereinafter, I attain in the following manner, reference being had to the accompanying drawings in which—

Figure 1 is an elevation of my improved spark plug.

Fig. 2 is a section on the line *a—a* of Fig. 1.

Fig. 3 is a bottom plan view of Fig. 1.

Fig. 4 is a fragmentary view of a portion of my spark plug showing a different arrangement of holes than is shown in Figs. 1 to 3 inclusive.

Fig. 5 is an end view of Fig. 4 showing the shape and location of said holes.

Referring to the drawings, 1 is a hollow body portion being externally screw-threaded at 2 so as to fit a tapped opening in an internal combustion engine or the like.

The body portion 1 is internally screw-threaded at 3 at its upper end, and is provided with an angular shoulder 4 which forms a thrust bearing for a jacket 5 which snugly fits within a bore 6 in the interior of said body portion 1.

The jacket 5 is recessed at 7 and is provided with a hole 8 which intersects said recess and extends to the inner surface 9. The hole 8 is of smaller diameter than the recess 7, so that an enlarged annular portion 10 of a porcelain 11 rests upon the shoulder 60 12 formed by the intersection of said hole 8 with the recess 7.

The lower portion 13 of the porcelain 11 fits the hole 8, and the space between the upper portion 14 of the porcelain and the 65 walls of the jacket forming the recess 7 is filled with cement as shown at 15.

A nut 16 has a depending threaded stem 17 which engages the internal screw-thread 13 of the body portion 1, and the lowermost portion of said stem 17 engages the upper surface 18 of the jacket 5. The nut 16 has a hole 19 of larger diameter than the upper portion 14 of the porcelain 11, so that while the stem portion 17 of the nut 16 engages the 75 upper surface 18 of the jacket 5, the nut will be entirely free of the porcelain 11, so that said nut may forcibly engage the upper surface 18 of the jacket 5 to force the latter against the shoulder 4 without cracking or 80 otherwise injuring the porcelain 11.

The porcelain 11 has extending upwardly therethrough an electrode 20, said electrode being threaded at 21 at its upper end and provided with a binding nut 22.

The electrode 20 is located adjacent an adjustable electrode 23, the latter being secured to a screw 24 which fits within a tapped opening 25 in the lower part 26 of the body portion 1. A chamber 27 is thus 90 provided and the chamber 26 communicates with the upper surface 28 of the body portion 1 through the medium of perforations 29.

These perforations 29 are substantially 95 elliptical and taper inwardly as clearly shown in Fig. 2. The perforations thus formed intersect the interior surface in practically a knife edge 30, so that any carbon or other deposit which may collect 100 thereon quickly burns and is blown off due to the action of the explosions within the engine. The perforations are thus kept clear from any carbon deposit at the point where they enter the chamber 27, and by 105 having the entire portion 26 closed, it is impossible for the explosions of the engine to directly effect the electrodes 20 and 23.

2
The perforations 29 as shown in Figs. 1 to 3 inclusive are so positioned that when the plug is used as a vertical plug or has its axis in alinement with the axis of the piston 5 of the engine, they will not be in direct line with the explosion, and will not receive the first impact of the explosion. However, when I use my improved plug in a horizontal position or in any position in which the longitudinal axis extends at an angle to the axis of the piston, I preferably locate the perforations in the part 26 of the body portion 1 as is shown at 31 in Figs. 4 and 5.

In all other respects the construction of Figs. 4 and 5 is similar to that disclosed in connection with Figs. 1 to 3 inclusive, and I have therefore given the parts the same reference numerals.

As a convenience, I preferably provide 20 the screw 24 having the electrode 23 thereon, with a slot 32 so that the electrode 23 may be adjusted toward or from the electrode 20. The chamber 27 is preferably made of large diameter so as to form a large 25 amount of clearance around the porcelain 11 and electrodes 20 and 23.

By having the end 26 closed and forming a closure for the lower part of the porcelain and the electrodes 20 and 23, practically no 30 carbon is deposited upon said porcelain or electrodes, the perforations 29 providing ample opening for the ignition of the gases by the spark, so that the entire interior of the chamber 27 is kept clean.

35 Furthermore, it is only the lighter portion of the gases which surrounds the body portion 1, and therefore any carbon which forms a deposit on the surfaces forming the perforations is quickly burnt and blown off 40 as above described. Furthermore, practically no strain is placed upon the porcelain 11, and the shoulder 4 is preferably made angular so that the jacket 5 will properly seat itself without any chance of variation.

45 The clearance which is provided by the hole 19 in the nut 16 allows for any irregularities in the porcelain 11, so that the latter practically is mounted in the jacket 5 and is in reality suspended but firmly held 50 therein.

The body portion 1 may be made of any metal which is a good conductor of electricity as may also be the electrodes 20 and 23. Furthermore, the jacket 5 may be made 55 of metal or other suitable material, the porcelain 11 acting as an insulating member for the electrode 20.

In the claims I have stated that the hole 19 in the nut 16 is of larger cross section 60 than the insulating porcelain or member 11, but it will be understood that it is only the portion of the insulating member 11 which passes through the hole 19 which is 65 of smaller cross section than the hole and any of the other portions of the porcelain

such for example as the projection 10 may be of larger size than the hole 19 and the porcelain 11 may be of any shape desired.

While I have described my invention as taking a particular form, it will be understood that the various parts of my invention may be changed without departing from the spirit thereof, and hence I do not limit myself to the precise construction set forth, but consider that I am at liberty to 75 make such changes and alterations as fairly come within the scope of the appended claims.

Having thus described my invention, what I claim as new and desire to secure 80 by Letters Patent is:

1. A spark plug comprising a hollow body portion closed at one end and having perforations adjacent said end, electrodes positioned within said hollow body portion, 85 means for retaining the electrodes, said body portion having perforations adjacent said closed end, said perforations being tapered inwardly to produce continuous sharp edges, said edges being formed by the intersection 90 of the perforations and the inner wall of the body portion, substantially as described.

2. A spark plug comprising a hollow body portion closed at one end and having perforations adjacent said end, electrodes positioned within said hollow body portion, 95 means for retaining the electrodes, said body portion having perforations adjacent said closed end, said perforations being substantially elliptical in shape and being 100 tapered inwardly to produce continuous sharp edges at their points of intersection with the inner surface of said body portion, substantially as described.

3. A spark plug including a casing having 105 an opening terminating in a shoulder, a jacket fitting said opening and abutting said shoulder, said jacket having a hole through its inner end and a recess of larger cross section than and intersecting said hole to 110 provide a shoulder, an electrode-insulating member extending through said hole, said member having a projection resting on said shoulder of the jacket, said recess extending to the opposite end of the jacket and being 115 of sufficient cross section throughout its entire length to permit said projection to be free to move into or out of it, cement filling the space between said member and the inner wall of the recess, and means having a portion in engagement with said jacket to 120 impart thrust thereto to firmly seat said jacket against the shoulder in the casing, said latter portion being free of the recess, substantially as described.

4. A spark plug including a casing having an opening terminating in a shoulder, a jacket fitting said opening and abutting said shoulder, said jacket having a hole through its inner end and a recess of larger cross 130

- section than and intersecting said hole to provide a shoulder, an electrode-insulating member extending through said hole, said member having a projection resting on said shoulder of the jacket, said recess extending to the opposite end of the jacket and being of sufficient cross section throughout its entire length to permit said projection to be free to move into or out of it, cement filling the space between said member and the inner wall of the recess, a nut having a threaded stem fitting said casing, said stem having a portion in engagement with said jacket to impart thrust thereto to firmly seat said jacket against the shoulder in the casing, said latter portion being free of the recess, substantially as described.
5. A spark plug including a casing having an opening terminating in a shoulder, a jacket fitting said opening and abutting said shoulder, said jacket having a hole through its inner end and a recess of larger cross section than and intersecting said hole to provide a shoulder, an electrode-insulating member extending through said hole, said member having a projection resting on said shoulder of the jacket, said recess extending to the opposite end of the jacket and being of sufficient cross section throughout its entire length to permit said projection to be free to move into or out of it, cement filling the space between said member and the inner wall of the recess, a nut having a threaded stem fitting said casing, said stem having a portion in engagement with said jacket to impart thrust thereto to firmly seat said jacket against the shoulder in the casing, said latter portion being free of the recess, said nut having an inwardly flared opening, said insulating member having an outwardly tapered portion extending through said flared opening and spaced therefrom, substantially as described.
6. A spark plug including a casing having an opening terminating in a shoulder, a jacket fitting said opening and abutting said shoulder, said jacket having a hole through its inner end and a recess of larger cross section than and intersecting said hole to provide a shoulder, an electrode-insulating member extending through said hole, said member having a projection resting on said shoulder of the jacket, said recess extending to the opposite end of the jacket and being of sufficient cross section throughout its entire length to permit said projection to be free to move into or out of it, cement filling the space between said member and the inner wall of the recess, a nut having a threaded stem fitting said casing, said stem having a portion in engagement with said jacket to impart thrust thereto to firmly seat said jacket against the shoulder in the casing, said latter portion being free of the recess, said nut having an opening, said insulating member having an outwardly projecting portion extending through said opening and spaced therefrom, substantially as described.
7. A spark plug including a casing having an opening terminating in a shoulder, a jacket fitting said opening and abutting said shoulder, said jacket having a hole through its inner end and a recess of larger cross section than and intersecting said hole to provide a shoulder, an electrode-insulating member extending through said hole, said member having a projection resting on said shoulder of the jacket, said recess extending to the opposite end of the jacket and being of sufficient cross section throughout its entire length to permit said projection to be free to move into or out of it, cement filling the space between said member and the inner wall of the recess, and means having a portion in engagement with said jacket to impart thrust thereto to firmly seat said jacket against the shoulder in the casing, said latter portion being free of the recess, said means having an inwardly flared opening, said insulating member having an outwardly tapered portion extending through said flared opening and spaced therefrom, substantially as described.
- In testimony whereof I have signed my name to this specification in the presence of two subscribing witnesses.
